UNITED STATES PATENT OFFICE.

ALEXANDER S. SPIEGEL, OF CHICAGO, ILLINOIS.

APPARATUS FOR MAKING PREPARED ROOFING.

1,301,332.

Specification of Letters Patent. Patented Apr. 22, 1919.

Application filed October 5, 1918. Serial No. 257,078.

To all whom it may concern:

Be it known that I, ALEXANDER S. SPIEGEL, a citizen of the United States, and resident of Chicago, Illinois, have invented certain new and useful Improvements in Apparatus for Making Prepared Roofing, of which the following is a specification.

My invention relates to the manufacture of roofing and particularly to a machine for cutting a web of prepared roofing material into roofing elements.

The invention consists in the features and combination and arrangement of parts hereinafter described and particularly pointed out in the claims.

In the accompanying drawings,

Figure 1 represents one of the elements in the making of which my invention plays a part.

20 Fig. 2 is a plan view of a portion of a web of the roofing material showing in dotted lines longitudinal slots which my present apparatus is designed to make in the webbing. This view also indicates in dotted lines, extending transversely of the web, the points at which the web is cut in order to form in connection with the longitudinal slots shown in dotted lines the element of Fig. 1.

30 Fig. 3 is a view of the rotary cutters, the lower rotary cutter being shown in section and these cutters being adapted to receive the web fed between them for cutting the longitudinal slots therein.

35 Fig. 4 is a view at right angles to that of Fig. 3.

Fig. 5 is a detail of a part of the upper and lower cutters.

Fig. 6 is a face view of the lower cutter.

40 In these drawings 1 indicates a roller having ribs or cutters 2 projecting from its surface and extending in a direction circumferentially, but only partly around the peripheral face of the roll or disk. 3 indicates

45 the complementary cutter, or die element, which is of hollow form, and is provided with die openings 4 properly spaced apart to conform to the spacing of the punching ribs or cutters 2 of the disk or roller 1.

50 There are a series of these cutters 2 and die openings 4 disposed at different points along the axis of the upper and lower punch and die elements, so that the slots indicated at *a* in Fig. 2 will be formed by the passage of 55 the web of roofing material between these cutting elements. This roofing material is

of the type which has a thick pasty asphalt coating, and a grit surface, and the cutting elements must be specially formed to handle material of this character. I therefore make 60 the punch rib 2 of the upper roll or element of the dove-tail form in cross-section, shown in Fig. 5, and the die opening 4 of the lower cutting element is also made dovetail in cross-section and as a result of this formation the piece of material cut from the web in making the slot therein will not stick in the die opening and gum up and finally prevent proper cutting actions being performed, but these cut portions will be cleared 70 from the die openings 4 and will fall away through the interior of the lower die roll, or disk. The flaring form of the die opening I prefer to make both laterally and longitudinally, so that a clearance will be left 75 all around this die immediately in rear of the entrance to the die opening to secure a good clearance at all points, as indicated in dotted lines in Fig. 6.

While I prefer to make the punch rib of 80 the dove-tailed form in cross section and also longitudinally, I may employ a cutter or punch of a rectangular form in cross section. The punch of dove-tailed form will clear itself from the opening it punches in 85 the material better than will a punch having its side faces at right angles to its cutting face.

It will be understood that the cutters above mentioned are used in connection with 90 suitable means for feeding the material or web between said cutters and any suitable means may be embodied in the machine for severing the web transversely, for instance, on the lines *b*—*b* of Fig. 2, so that the article 95 of Fig. 1 will be produced.

There may be a series of the disks arranged side by side, or if a roll is used the die openings, and likewise the punches, are spaced apart along the same.

100 What I claim is;

1. A machine for cutting a web of prepared roofing material of the type which has a thick pasty asphalt coating and a grit surface comprising a pair of rotary members, one of which has punching ribs extending circumferentially thereof, but of a length less than the circumference of the member and a second member having a complementary die opening to coact with the 105 punching rib, said die opening flaring in a direction away from the entrance for the 110

punch, and communicating with a free space adjacent its larger side for the discharge of the cuttings substantially as described.

2. A machine for cutting a web of prepared roofing material of the type which has a thick pasty asphalt coating and a grit surface comprising a rotary punch member having a circumferentially disposed punch rib, a rotary die member having a die opening 5 to receive said rib, said opening being flared 10 away from the mouth through which the punch enters and communicating with the open interior of the member for the discharge of the cuttings, the said punch rib 15 being of dove-tail form in cross-section substantially as described.

3. In a combination in a machine of the class described a punch roll having a punch rib extending circumferentially thereof, a die roll having an opening to receive the 20 punch, said punch and die opening being of dovetail formation, both transversely and longitudinally, and said die opening communicating at its larger end with an adjacent free space for the discharge of the 25 cuttings, substantially as described.

In testimony whereof, I affix my signature.

ALEXANDER S. SPIEGEL.

Witnesses:

WILLIAM E. HARTMAN,
ALEXANDER BARRIE.
